US0D1027856S

(12) **United States Design Patent** (10) **Patent No.:** **US D1,027,856 S**
(45) **Date of Patent:** **** May 21, 2024**

(54) **POWER CONVERSION APPARATUS**

(71) Applicant: **LG Electronics Inc.**, Seoul (KR)

(72) Inventors: **Kyeongchul Cho**, Seoul (KR); **Yongho Lee**, Seoul (KR)

(73) Assignee: **LG ELECTRONICS INC.**, Seoul (KR)

(**) Term: **15 Years**

(21) Appl. No.: **29/834,296**

(22) Filed: **Apr. 11, 2022**

Related U.S. Application Data

(63) Continuation of application No. 35/509,954, filed on Jan. 29, 2020 (U.S. filing date under 35 U.S.C. 384), and having an international filing date of Jan. 29, 2020, now abandoned.

CLAIM

The ornamental design for a power conversion apparatus, as shown and described.

DESCRIPTION

FIG. 1 is a front, right perspective view of the power conversion apparatus showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the power conversion apparatus that form no part of the claimed design.

1 Claim, 7 Drawing Sheets
